UNITED STATES PATENT OFFICE.

JAMES A. GIESE, OF CHICAGO, ILLINOIS, ASSIGNOR TO THE ADAMS & WESTLAKE COMPANY, OF CHICAGO, ILLINOIS, A CORPORATION OF ILLINOIS.

DOOR.

1,079,121.

Specification of Letters Patent. Patented Nov. 18, 1913.

Application filed June 7, 1912. Serial No. 702,235.

To all whom it may concern:

Be it known that I, JAMES A. GIESE, a citizen of the United States, and resident of Chicago, county of Cook, and State of Illinois, have invented certain new and useful Improvements in Doors, of which the following is a specification, and which are illustrated in the accompanying drawings, forming a part thereof.

10 The invention relates to doors having the latch casing housed within them, and being especially applicable to hollow metal doors.

In the manufacture of metal doors, such as are now in quite common use in railway cars and other situations, it has been found difficult to permanently and satisfactorily secure the latch casing within the chamber of the door. The more common expedient 20 of fitting within the door a mortised block to which the face plate of the latch casing has been attached, has been attended with serious difficulties in practice, due to the tendency of the attaching screws to work loose,—the inability to relieve the latch-controlling spindle of the duty of maintaining the latch in place, and for other reasons.

The object of this invention is to overcome these difficulties by securing the latch casing to the side walls of the door; and the invention consists in a device as hereinafter described and as illustrated in various forms in the drawings, in which—

Figure 1 is a detail plan section of the door and door jamb taken above the latch casing, a part of this casing being shown in plan section; Fig. 2 is a detail perspective of the door and latch casing, some parts being removed and some parts being in section; Fig. 3 is a detail in perspective of the latch-controlling spindle and of an escutcheon plate, the latter being shown in section; Fig. 4 is a sectional detail in perspective of the door showing a modified form of construction; Fig. 5 is a detail in perspective of the door showing a still further modification; and Fig. 6 is a detail in perspective of the spindle and an escutcheon plate used in connection with the device.

60 As illustrated in Fig. 1 the door is shown as being of metal and comprising a pair of side or wall plates 10, 11, spaced apart and inclosing a chamber, and an edge wall 12. The last-named wall is apertured to permit 65 the insertion of a latch casing 13, which

may be provided with the usual face plate 14 and, if desired, screwed to a supporting plate 15 attached to the inner face of the wall 12 and overlapping its opening. An escutcheon plate 16 is applied to the outer 60 face of one of the walls, as 11, of the door, and is provided with a plurality of studs, as 17, 18 and 19, which project through this wall. The latch casing 13 is provided with a lug, here shown at 20, projecting from the 65 inner end of the casing and engaging the end of the stud 17, to which it is secured by a screw 21, its face plate 14 being held snugly against the seating plate 15. The wall 10 of the door is apertured, as shown 70 at 22, to provide access to the screw 21, and this aperture is covered by an escutcheon plate 23 having instanding studs 24, 25, which are in alinement and telescopic engagement with the studs 18, 19. Screws, 75 as 26, set through the escutcheon plate 23, enter threaded sockets in the studs 18, 19, and draw the two escutcheon plates toward each other. The threaded sockets of the studs 18, 19, are of sufficient depth to permit 80 the screws to be set up so as to slightly compress the plates 10, 11, of the door, whereby these plates by their elasticity serve to securely hold the screws against turning under the influence of jars and vibrations. The 85 latch-controlling spindle 27 may be of any desired form and passes through the escutcheon plates 16 and 23. The latch is, however, securely held in position by the means described, so that the spindle is not 90 called upon to maintain it in position, and it is therefore free to turn in its bearings.

In the construction illustrated in Fig. 4, both of the escutcheon plates, here designated by the numerals 28, 29, are provided 95 with instanding studs for attachment to the lug 20 of the latch casing. In this instance the securing means is a screw 32 set through one of the escutcheon plates, as 29, through its stud 31, the lug 20, and into the 100 stud 30, with which it makes threaded engagement. By making the studs 30 and 31 of such length that they do not normally reach the lug 20, the plates 10, 11, may be 105 slightly compressed for the purpose of securing the proper spring action for preventing the screw from working loose. When this form of construction is followed, it becomes unnecessary to provide the aperture, as 22, in the wall plate 10, this plate being aper- 110

2
tured to accommodate the studs, as 33, 34, which coöperate with the studs 35, 36, of the escutcheon plate 28 in securing the two escutcheon plates together.

5 In the construction illustrated in Figs. 5 and 6, the latch casing, here designated 37, is provided with a plurality of lugs, as 38, 39 and 40, each having a threaded aperture for receiving screws, as 41, 42, 43, set directly through the side walls 10, 11, of the door, and tending to draw them up with a compressive action while securely holding the latch casing in place. An escutcheon plate as 44 may be applied to each side of 10 the door for covering the heads of the latch securing screws.

I claim as my invention—

1. In combination, a hollow metal door, a latch casing housed within the door and being of less thickness than the distance between the side walls thereof, escutcheon plates applied to the door and having studs 20 passing through the walls thereof, the inner ends of the studs being normally spaced 25 apart, from the casing, and screws securing the studs to the casing.

2. In combination, a hollow metal door, a latch casing housed within the door and being of less thickness than the distance between the side walls thereof, escutcheon plates applied to the side walls of the door and having studs passing therethrough, studs of the two plates being alined and their inner ends being normally out of contact, screws securing such alined studs together, and means for securing the casing to one of the plates.

3. In combination, a hollow metal door, a latch casing housed within the chamber of the door, means for securing the casing to one of the side walls of the door, the other side wall of the door being apertured to afford access to the casing, an escutcheon plate covering the aperture and flanged to overlap the margins thereof, and means for securing the escutcheon plate to the opposite wall of the door.

JAMES A. GIESE.
